UNITED STATES PATENT OFFICE

ARNOLD H. MOECKER, OF FLOSSMOOR, ILLINOIS, ASSIGNOR TO AMERICAN STOVE COMPANY, OF ST. LOUIS, MISSOURI, A CORPORATION OF NEW JERSEY

DESIGN FOR A RANGE

Application filed August 22, 1929. Serial No. 32,503. Term of patent 14 years.

To all whom it may concern:

Be it known that I, ARNOLD H. MOECKER, a citizen of the United States, residing at Flossmoor, in the county of Cook and State of Illinois, have invented a new, original, and ornamental Design for Ranges, of which the following is a specification, reference being had therein to the accompanying drawing in

which the figure is a perspective view of a range, showing my new design.

I claim:

The ornamental design for a range, as shown.

In testimony whereof, I hereunto affix my signature.

ARNOLD H. MOECKER.
